UNITED STATES PATENT OFFICE.

WILLIAM T. LOWRANCE, OF MONTE VISTA, COLORADO.

FENCE-POST.

1,312,448.

Specification of Letters Patent.

Patented Aug. 5, 1919.

Application filed November 13, 1918. Serial No. 262,375.

To all whom it may concern:

Be it known that I, WILLIAM T. LOWRANCE, a citizen of the United States, residing at Monte Vista, in the county of Rio Grande and State of Colorado, have invented certain new and useful Improvements in Fence-Posts; and I do hereby declare the following to be a full, clear, and exact description of the invention, such as will enable others skilled in the art to which it appertains to make and use the same.

This invention relates to fence posts, and more particularly to a fence post which is constructed of steel or other suitable metallic material.

One of the main objects of the invention is to provide a fence post of simple construction and operation which may be produced at small cost and possesses relatively great strength.

A further object is to provide a post having a relatively large base which may be readily driven into the ground and acts to firmly secure the post in position.

Another object is to provide a post comprising a body and a base and means for securing these members together, the securing means being adapted to permit detaching of the body from the base when required or necessary.

Further objects will appear from the detailed description.

In the drawings:

Figure 1 is a front view of a post constructed in accordance with my invention in assembled position.

Fig. 2 is a side view of the same.

Fig. 3 is a section taken substantially on line 3-3 of Fig. 1.

Fig. 4 is a section taken on line 4-4 of Fig. 1.

Fig. 5 is a section taken on line 5-5 of Fig. 2.

Fig. 6 is a detail underneath plan view of the cap plate.

Fig. 7 is a section taken substantially on line 7-7 of Fig. 1.

Fig. 8 is a detail perspective view of the base.

The post comprises a body 1 which is formed from relatively heavy scrap iron or steel and is of rectangular shape in cross section, and a base 2 upon which this body is secured. This base is of substantial Z-shape in cross section, being formed by stamping and bending from strap metal of

suitable gage and temper so as to provide the outer oppositely directed lateral arms 3 and the diagonal connecting web portion 4. The lower ends of the arms and the web are beveled to produce relatively sharp cutting edges so as to facilitate driving of this base into the ground.

Each of the lateral arms 3 is provided, at its upper outer corner, with a vertically extending tab 5 which is adapted to fit snugly through a corresponding slot provided through a substantially rectangular cap plate 6 adapted to fit snugly upon the top of the base. This cap plate is provided with a central diagonal slot 7 which is adapted to receive the lower bifurcated portion 1^a of body 1. This lower bifurcated portion of the body produces two spaced parallel arms 1^b which are adapted to fit tightly about the upper portion of web 4 at the transverse center thereof. As will be noted more clearly from Fig. 5, each of these arms is slightly offset to provide a downwardly and outwardly inclined connecting shoulder 1^c so that, by forcing the cap plate into tight engagement therewith all spreading of these arms is effectually prevented. In practice, the lower bifurcated portion 1^a of the body 1 of the post is inserted over the web 4, the cap plate 6 being first loosely placed about this body and fitted over the tabs 5 so as to be properly centered. The arms 1^b are then releasably secured to the web by means of securing bolts 8 inserted therethrough.

When this has been done, the cap plate is driven down so as to be seated upon the upper end of the base, the tabs being bent over slightly to effectually secure the cap plate against all movement or play, this plate acting to brace the body of the post and to also prevent any spreading or distortion of the arms 3 of the base. When the post has been thus assembled, the base 2 thereof may be driven into the ground by striking the top of the post with any suitable tool, the base being preferably, though not necessarily, driven into the ground to such a depth as to bring the cap plate 6 substantially flush with the ground surface. Because of its particular shape, the base obtains a very firm grip in the ground and serves to tightly anchor the post against movement.

As will be noted more clearly from Figs. 1 and 2, the body 1 of the post is provided with a plurality of wire receiving slots 9 extending inwardly from the forward edge

thereof and being alternately and oppositely inclined. These slots communicate with substantially circular openings 10, at their inner ends, for receiving the strands of wire to be secured. When using the post, it is set up with the slotted edge portion directed toward the fence to be strung, the body of the post being disposed substantially at right angles to the strands of wire. The wire strands are then tightened in any of the many well known ways and are forced into the inclined slots 9 and the openings 10 the upper and lower walls of which are also inclined similarly to the slots, thus forming a sharp bend in the wire which is tightly gripped between the two gripping edges produced by the inclined openings and effectually secured against all looseness or play. By having the slots alternately and oppositely inclined, the post is effectually braced by the wires against all lateral play, while any strain which may be caused by pressure along lines at right angles to the fence, or substantially so, will be transmitted to the body of the post transversely thereof. The post being comparatively wide is well able to withstand all of these transverse strains and, as above noted, it is securely braced against lateral strain by the action of the strands of wire themselves secured to the post. If at any time it becomes necessary, or is desired, to remove the post, this may be readily accomplished by removing the securing nuts 11 from the bolts 8, previously straightening the tabs 5 and removing the cap plate 6. When this has been done, the body of the post may be readily detached

from the base so as to be applied to a similar base and secured thereby in the desired new location. Also, in the event of the body of the post becoming bent or broken, it may be readily replaced in the manner previously described for securing the body to the base, the broken or injured post body being first detached, as will be understood.

It will be evident that there may be slight changes made in the construction and arrangement of the details of my invention without departing from the field and scope of the same, and I intend to include all such variations, as fall within the scope of the appended claim, in this application in which a preferred form only of my invention is disclosed.

What I claim is:

In a post of the character described, a base of substantial Z-shape in cross section, a post body having its lower end portion bifurcated and fitting snugly about the upper end portion of the web of the base, a cap plate 6 provided with a slot receiving said body and fitting tightly about the bifurcated portion thereof so as to brace the same, and means for detachably securing the cap plate to the arms of the base so as to brace the same 6 against lateral movement or distortion and hold the post body in proper centered position.

In testimony whereof I affix my signature in presence of two witnesses.

WILLIAM T. LOWRANCE.

Witnesses:

SAMUEL S. HEILMAN,
RALPH B. PATTERSON.
